Benjamin Ruggles - Person.

9698X Setters Patent

The Schedule referred to in the Setters Patent and making part of the same containing a description in the words of the said Benjamin Ruggles himself, of his improvement in the blast furnace for smelting iron and other ores.

In all Artisan or Trade, be it known that I, Benjamin Ruggles, of the City of Philadelphia in the State of Pennsylvania have invented an improvement in the construction of blast furnaces for the smelting of iron ore, or the ores of other Metals with Anthracite Coal or with other fuel hard. I do hereby declare that the following is a full and true description thereof.

In describing the improvement, which I have made, I shall for the purpose of giving a clear illustration of the principle upon which I have resorted to the drawings which accompanies this Specification. Without introducing thereby to limit myself to the particular forms and arrangements exhibited as the blast furnace which I now may be built in any of the common forms, and which in its dimensions as well as in the mode of arranging the respective parts A in the accompanying drawing, represent the main furnace or stack and B.B. are small chambers or stacks which are to be filled with fuel. These chambers may vary considerably in their dimensions and form, but I prefer to make them about a foot square in the clear and six feet in height C.C. are tuyere holes, and the tube passes the tuyere holes, into which the hollow pipe C.C. enters may like the other parts of the furnace vary in their dimensions but I intend to make them about two inches in diameter on the outside gradually contracting to a diameter of six inches. A blast of air passes the tuyere holes into which the hollow pipe C.C. enters may like the other parts of the furnace vary in their dimensions but I intend to make them about two inches in diameter on the outside gradually contracting to a diameter of six inches. A blast of air passes the tuyere holes into which the hollow pipe C.C. enters may like the other parts of the furnace vary in their dimensions but I intend to make them about two inches in diameter on the outside gradually contracting to a diameter of six inches. When the furnace is used the main body is charged with coal, the ore and the fueling materials in the usual way, and the small stacks B.B. are filled with Anthracite Coal or other fuel. When this is ignited and the blast is made to pass through it the furnace heats very intensely so that when it passes the tuyere holes of the main stack the charring of the slag which the ordinary blast produces, is entirely obviated as the air is actually at the temperature of perfect ignition.

N.D.D.P. are mounted tops and bottoms of the small stack for feeding and cleaning when it becomes necessary. Then it will stay to the permanent against the main stack as shown in the drawing, but it will be found more convenient to place them upon trunnions so that they may be taken off when it is necessary to repair the inner tube in the main stack. When re-placed they are to be firmly attached by flauncher nuts, screws or key bolts, or in any other way, article may be preferred, as proper comment is to be interposed between the two at the place of junction.

Having thus fully described my said invention I do hereby declare that all I claim as my improvement and desire to secure by letters Patent is the use of the small chambers or stacks placed opposite to any or all of the tube holes in the main stack operating in the manner described for the purpose set forth namely that the blast from the bellows may first pass through igniter fuel before it enters the main stack within which the coal, materials and fuel are contained and thus obviating a ready prevention and this I claim whatever may be the number of such small stacks and whatever their size or form or whether the size or form of the main stack and whatever the fuel used be whether solid coke or otherwise in respect of some other kind.
